(57) **CLAIM**

The ornamental design for a medical X-ray imaging apparatus, as shown and described.

DESCRIPTION

FIG. 1 is a top, front and left side perspective view of a medical X-ray imaging apparatus showing my new design; FIG. 2 is a top, rear and left side perspective view thereof; FIG. 3 is a front elevational view thereof; FIG. 4 is a rear elevational view thereof; FIG. 5 is a top plan view thereof; FIG. 6 is a bottom plan view thereof; FIG. 7 is a left side elevational view thereof; FIG. 8 is a right side elevational view thereof; FIG. 9 is a top, front and left side perspective view thereof in a state that an arm having an X-ray irradiation device at its distal end is folded; FIG. 10 is a top, rear and left side perspective view thereof in a state that an arm having an X-ray irradiation device at its distal end is folded; FIG. 11 is a front elevational view thereof in a state that an arm having an X-ray irradiation device at its distal end is folded; FIG. 12 is a right side elevational view thereof in a state that an arm having an X-ray irradiation device at its distal end is folded; FIG. 13 is an enlarged cross-sectional view thereof taken along lines XIII-XIII of FIG. 11, in which an internal mechanism is omitted; and, FIG. 14 is a top, rear and left side perspective view thereof, showing a state that an electronic cassette is put in a housing section such that the electronic cassette is charged. The broken lines in FIG. 14 depict environmental subject matter only and form no part of the claimed design.

1 Claim, 14 Drawing Sheets
